Primary Examiner — Jack Reickel*Assistant Examiner* — Rachel A Voorhies(74) *Attorney, Agent, or Firm* — Acuity IP, LLC; Nathan S. Cassell(57) **CLAIM**

The ornamental design for a rear fender molding for vehicle, as shown.

DESCRIPTION

FIG. 1 is a top perspective view of a rear fender molding for vehicle showing my new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The claimed rear fender molding for vehicle attaches to the rear fender of a vehicle.

1 Claim, 7 Drawing Sheets(56)
